CLAIM

We claim the ornamental design for a control device, as
shown and described.

DESCRIPTION

FIG. 1 is a perspective view of a control device showing our
new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a control device showing a
second embodiment of our new design; and,

FIG. 8 is a front view thereof.

The left side, right side, top and bottom views of the second
embodiment are identical to the left side, right side, top, and
bottom views of the first embodiment.

The rear view forms no part of the claimed design and is
omitted.

The uniform dashed broken lines illustrate structure or
features which form no part of the claimed design; the
broken lines themselves form no part of the claimed design.
